ELECTRIC DISCHARGE APPARATUS

Ralph N. Stoddard, Pittsburgh, Pa., assignor to Westinghouse Electric & Manufacturing Company, East Pittsburgh, Pa., a corporation of Pennsylvania

Application March 13, 1937, Serial No. 130,755

10 Claims. (Cl. 175—294)

My invention relates to electric discharge apparatus and has particular relation to apparatus for interrupting an arc such as is produced by the opening of switch contacts.

5 It is an object of my invention to provide an arc interrupting system of simple and inexpensive structure.

Another object of my invention is to provide an arc interrupting system entirely devoid of 10 mechanical contacts.

An ancillary object of my invention is to provide a highly certain and efficient means for 15 initiating the discharge in a discharge device of the type comprising a mercury pool cathode and a starting electrode composed of boron carbide or silicon carbide to cooperate with the cathode.

More specifically stated, it is an object of my 20 invention to provide a system for interrupting the arc produced at the contacts of a switch or circuit breaker, which shall not incorporate auxiliary contacts to be actuated in timed relationship with the contacts of the switch or circuit breaker.

According to my invention, I provide a system 25 incorporating an electric discharge device provided with a control electrode and a plurality of principal electrodes. The discharge device is of the arc-like discharge type, and its operating characteristic is such that for the proper control potential, the drop in potential across an 30 open air arc, such as is produced by opening a power switch, is sufficient to initiate a discharge between the principal electrodes. The difference in potential between the principal electrodes when 35 a discharge is thus initiated is substantially smaller than the drop in potential across the arc. Therefore, when a discharge is produced between the principal electrodes, the arc is extinguished.

In the preferred practice of my invention, the 40 discharge device utilized is of the Ignitron tube type. The latter comprises an anode, a mercury-like cathode and a starting electrode of the silicon carbide type, which dips into the cathode. By the expression "mercury-like cathode," I 45 mean a cathode composed of mercury or an element similar to it. The most common example of such an electrode is a pool of mercury. However, other metals such as cadmium and lead, for example, may be utilized and are contemplated as lying within the scope of my invention. By 50 the expression "a starting electrode of the silicon carbide type," I mean a starting rod which is dipped into the mercury-like electrode and through which a current is transmitted to initiate a discharge between the anode and the cathode.

A silicon carbide rod is the most common example of such an element. However, I have found that numerous other compounds may be utilized. Among these the most common are boron and boron carbide. I contemplate within the scope 5 of my invention, discharge devices incorporating starting rods of any suitable type.

While the discharge devices of the Ignitron tube type are preferable in the practice of my invention, occasions may arise for the use of discharge devices of other types. For example, under certain circumstances, it may be possible to utilize a hot cathode gaseous discharge device of the arc-like type, such as a Thyratron tube or a grid glow tube. While the Ignitron tube has certain peculiar advantages, the use of discharge devices of other types in accordance with my invention are contemplated as lying within the scope of my invention.

In the practice of my invention, the anode and the cathode of the discharge device utilized are connected directly across the region in which the arc to be extinguished is produced. The starting electrode and the cathode of the discharge device are also connected across the same region 20 through a tuned network. When the arc is produced, high frequency current passes through the tuned network and for the proper polarity of anode cathode potential, the discharge device 25 is energized and extinguishes the arc.

In accordance with an ancillary feature of my invention, the discharge in the discharge device is initiated by a contrivance which I have found to be simple and efficient. The network in the starting circuit is tuned to a frequency such that 30 the starting electrode has the maximum skin effect. Accordingly, the starting current flows near the surface of the starting electrode and is highly effective in initiating the main discharge.

The novel features that I consider characteristic of my invention are set forth with particularity in the appended claims. The invention itself, however, both as to its organization and its method of operation, together with additional objects and advantages thereof, will best be understood from the following description of specific embodiments when read in connection with the accompanying drawing, in which

Figure 1 is a diagrammatic view showing an embodiment of my invention;

Fig. 2 is a graph illustrating the operation of 50 my invention, and

Fig. 3 is a diagrammatic view showing a modification of my invention.

The apparatus shown in Fig. 1 comprises a 55

conductor 5 through which it may be assumed that alternating current is transmitted. The conductor 5 may be opened under certain circumstances by the disengagement of the movable contactor 7 of a circuit breaker 9, which may be regarded as symbolical of a circuit interrupter of any general type, from corresponding fixed contacts 11. The circuit-breaker operating mechanism may be of any well known type and since it does not concern the present invention will not be discussed in detail here.

When the contacts 7 and 11 of the circuit breaker 9 are opened, an arc is produced and to break the arc an electrode discharge device 13 is provided. The discharge device has an anode 15 composed of an element such as nickel or carbon, a cathode 17 of mercury and a starting electrode 19 consisting of a rod of boron, boron carbide, silicon carbide or the like, which dips into the mercury. The anode 15 of the discharge device 13 is connected directly to one of the fixed contacts 11 and the cathode 17 is connected directly to the other. The starting rod 19 is connected to a fixed contact 11 of the circuit breaker 9 on one side through the mercury cathode 17 and on the other side through a network 21 consisting of a capacitor 23 and an inductor 25. The inductor and capacitor are so selected that the network 21 is tuned to a predetermined frequency.

30 The operation of the apparatus is illustrated in Fig. 2. In this graph, the sine curve 27 corresponds to the potential which would be impressed across the fixed contacts 11 if they were not bridged by the movable contactor 7. The same 35 potential would be impressed between the anode 15 and the cathode 17 of the discharge device 13. The polarity of the ordinates of the curve 27 correspond to the polarity of the potential impressed between the principal electrodes of the 40 discharge device. Accordingly, if the circuit breaker contacts 7 and 11 were open, the left hand half wave would impress a negative anode-cathode potential while the right hand half wave would impress a positive potential.

45 The actual potential across the contacts 11 is represented by the heavy line 29. At the beginning of the half cycle illustrated in Fig. 2, the contacts 7 and 11 are closed and the potential across the contacts is zero as represented by the 50 line 31 along the abscissa.

Let us assume now that the circuit breaker 9 is opened at an instant late in the negative half cycle. At this instant an arc is ignited between the contacts and the potential drop rises from 55 zero to the negative value corresponding to the potential drop across the open air arc. This is represented by the line 33 below the abscissa. The arc produced cooperates with the tuned network 21 to initiate a high frequency disturbance 60 in the circuit incorporating the tuned network, the starting electrode 19 and the cathode 17. The disturbance is illustrated in the lower portion of Fig. 2 by a high frequency wave 36.

While current is now being transmitted through the starting electrode 19 and the cathode 17, the discharge device is not energized because the anode-cathode potential is of improper polarity. The open air arc thus continues to burn until the 65 anode-cathode potential passes through zero and becomes positive, and its potential may be represented by the heavy sloped line 35 along curve 27. The anode-cathode potential then rises positively as the open air arc continues to burn until it attains a predetermined value. When this value 70 is attained the discharge device 13 is energized

and the potential drop across the fixed contacts 11 decreases to a comparatively small value as represented by the heavy line 37 above the abscissa. The magnitude of this new potential drop between the anode 15 and the cathode 17 and therefore across the contacts 11 is such that the arc between the contacts 7 and 11 is extinguished. The discharge devices then continue to pass current until the end of the positive half cycle during which it was energized and then it is extinguished. Since the arc between the contacts 7 and 11 is now also extinguished, and has been extinguished for the larger part of a half cycle, it is not reignited during the succeeding half cycle. The discharge device is not reignited during the 15 subsequent positive half cycle since in the absence of the arc no high frequency currents flow through the tuned circuit and thus the system is reverted to a deenergized condition with circuit breaker 9 open.

As I have indicated hereinabove, the network in series with the starting rod 19 is tuned to a predetermined frequency. I have found that it should be so tuned that the maximum skin effect is manifested in the conductivity of the rod. 25 When the frequency is such that the conductivity of the rod manifests the maximum skin effect, the current passing through the rod is most efficient in initiating the main discharge. If the frequency is higher, the current passes over the 30 surface of the rod and is not effective in energizing the discharge device. If it is lower, the current passes in a region well within the rod and while the main discharge will be ignited, the current required is generally considerably greater 35 than that required where the frequency corresponds to the maximum skin effect. The rods commonly utilized in discharge devices of the Ignitron tube type are $\frac{3}{8}$ inch in diameter and one inch long, and I have found that for these the 40 network should be tuned to a frequency of the order of 150,000 cycles.

As is apparent from Fig. 2, there is some delay in the extinction of the arc produced at the contacts 7 and 11 of the circuit breaker 9 when only 45 a single discharge device 13 is connected across the fixed contacts. If this delay is undesirable, a pair of discharge paths may be utilized to replace the single one of the embodiment of Fig. 1.

A system for instantaneously extinguishing the 50 arc is illustrated in Fig. 3. Here, a pair of discharge devices 39 and 41 are provided. The discharge devices are connected in anti-parallel so that the anode-cathode polarity of one of them always corresponds to the anode-cathode polarity 55 which would exist across the fixed contacts 11 were they open. The tuned network 21 is now connected between the starting electrodes 19 of the discharge devices and through the corresponding cathodes 17 to the fixed contacts 11 of 60 the circuit breaker. When the circuit breaker is opened and an arc is ignited, high frequency impulses pass back and forth in the circuit including the cathodes 11, the starting rods 19 and the tuned network 21. The discharge device for 65 which the anode-cathode potential is of the proper polarity is then immediately energized and the arc is extinguished in the same half cycle.

While in the embodiment shown in Fig. 3, two 70 distinct discharge devices 39 and 41 are shown as utilized, they may be replaced by a single discharge device having a pair of mercury-like cathodes into each of which starting rods dip. When one of the cathodes is positive and the other is negative, the former functions as an anode and 75

the latter as a cathode so that a discharge may be ignited between the two by the starting rod immersed in the latter. When the polarities are reversed, the former cathode becomes an anode and the former anode becomes a cathode.

While my invention has herein been illustrated as applied to the extinction of an arc produced by switching or circuit breaker operations, it should be recognized that it has certain broader aspects. For example, it may be applied in apparatus in which a discharge device of the Ignitron tube type is to supply power. Under such circumstances, an arc may be produced in a spark gap or other device and utilized to ignite the discharge device. My invention may also be applied in resistance welding. In this field of application, the contacts 7 and 11 may be replaced by a drum contact or may be associated with a suitable timer so that the conductor 5 is periodically open circuited and closed circuited. The welding electrodes are connected to conductor 5 and the arcing stress on the interrupting contacts 7 and 11 is relieved by the discharge devices 39 and 41 (Fig. 3).

It is to be noted, moreover, that the network 21 is a series tuned network. In the structure specifically disclosed herein a network of this type is desirable because the discharge devices 13, 39 and 41 require transmission of current through the rods 18 for starting, i. e., the rods operate most efficiently for high current and low potential. Discharge devices of other types, such, for example, as grid controlled gaseous devices, which are contemplated as included within the scope of my invention may require high potential and low current for starting. When the latter discharge devices are utilized in the practice of my invention, the series tuned network 21 should be replaced by a parallel tuned network or a combination of series and parallel tuned networks.

Although I have shown and described certain specific embodiments of my invention, I am fully aware that many modifications thereof are possible. My invention, therefore, is not to be restricted except insofar as is necessitated by the prior art and by the spirit of the appended claims.

I claim as my invention:

1. Apparatus for interrupting the flow of current through a conductor comprising means to be actuated for producing an open gap in said conductor, a pair of separate sets of electrodes defining electric discharge paths connected in anti-parallel across the position in said conductor where said gap is to be opened, the potential drop across the electrodes of each of said discharge paths when it is energized being substantially smaller than the potential drop across an arc produced across said gap when said means is actuated, and means common to both said discharge paths for initiating an arc in the one corresponding to the direction of flow of current in said conductor at the instant that said gap is opened.

2. Apparatus for interrupting the flow of current through a conductor comprising means to be actuated for producing an open gap in said conductor, a pair of separate sets of electrodes defining electric discharge paths connected in anti-parallel across the position in said conductor where said gap is to be opened, the potential drop across the electrodes of each of said discharge paths when it is energized being substantially smaller than the potential drop across an arc produced across said gap when said means is

actuated, and means common to both said discharge paths and including a network cooperative with an arc across said gap to produce high frequency current flow for initiating an arc in the one corresponding to the direction of flow of current in said conductor at the instant that said gap is opened upon the opening of said gap.

3. Apparatus for interrupting the flow of current through a conductor comprising means to be actuated for producing an open gap in said conductor, an electric discharge path, defined by an anode, a mercury like cathode and including an electrode comprising a rod of the silicon carbide type dipping into the cathode between which and the cathode a current is conducted to initiate a discharge between said anode and cathode, said anode and cathode being connected across the position in said conductor where said gap is opened, the potential drop between said anode and cathode when a discharge is initiated therebetween being substantially smaller than the potential drop across an arc produced across said gap when said means is actuated, and means consisting of a network extending from one terminal of the gap, through impedances tuned to the frequency at which the current flowing through said electrode would have the maximum skin effect, said electrode, said cathode to the other terminal of said gap, for initiating a discharge between said anode and cathode upon the opening of said gap.

4. In combination, electric discharge path means comprising a cathode of the mercury type, a collecting electrode to cooperate with said cathode, and a rod electrode of the silicon carbide type dipping into said cathode between which and the cathode a current is to flow to initiate a discharge in said path means and means for transmitting between said rod electrode and said cathode a current of a frequency at which the electrode manifests the maximum skin effect to initiate said discharge.

5. In combination, electric discharge path means comprising a cathode of the mercury type, a collecting electrode to cooperate with said cathode, and a rod electrode of the silicon carbide type having a diameter of the order of $\frac{3}{8}$ " dipping into said cathode between which and the cathode a current is to flow to initiate a discharge in said path means and means for transmitting between said rod electrode and said cathode a current of a frequency of the order of 150,000 cycles to initiate said discharge.

6. In combination, electric discharge path means comprising a cathode of the mercury type, a collecting electrode to cooperate with said cathode, and a rod electrode of the silicon carbide type dipping into said cathode between which and the cathode a current is to flow to initiate a discharge in said path means and means including an arc and a tuned network connected across said arc for transmitting between said rod electrode and said cathode a current of a frequency at which the electrode manifests the maximum skin effect to initiate said discharge.

7. In combination, in effect, a pair of electric discharge path means connected in anti-parallel, each path means comprising in effect a cathode of the mercury type, a collecting electrode to cooperate with said cathode, and a rod electrode of the silicon carbide type dipping into said cathode between which and the cathode a current is to flow to initiate a discharge in said path means and means consisting of an arc and a network extending from one terminal of the arc, through

a cathode of one discharge path means, the corresponding rod electrode, a pair of impedances consisting of an inductor and a capacitor, the rod electrode of the other path means, the corresponding cathode to the other terminal of the arc, for initiating a discharge in either of said path means.

8. Apparatus according to claim 7, characterized by the fact that the inductor and capacitor are of such magnitude that current flows through the network at a frequency corresponding to the maximum skin effect of the rod electrodes.

9. Apparatus according to claim 7, characterized by the fact that the rod electrode has a diameter of the order of $\frac{3}{8}$ " and the inductor and capacitor are of such magnitude that current flows through the network at a frequency of the order of 150,000 cycles.

10. Apparatus for interrupting the flow of cur-

rent through a conductor comprising means to be actuated for producing an open gap in said conductor, a pair of separate sets of electrodes defining electric discharge paths connected in anti-parallel across the position in said conductor where said gap is to be opened, the potential drop across the electrodes of each of said discharge paths when it is energized being substantially smaller than the potential drop across an arc produced across said gap when said means is actuated, each said sets of electrodes including an ignition electrode in contact with one of the other electrodes of its set, and a single network interconnecting the ignition electrodes of each said set and responsive to the opening of said gap for initiating an arc in the one corresponding to the direction of flow of current in said conductor at the instant that said gap is opened.

RALPH N. STODDARD.
